UNITED STATES PATENT OFFICE.

WILLIAM W. SHOE, OF PHILADELPHIA, PENNSYLVANIA.

IRON.

1,099,401.

Specification of Letters Patent.

Patented June 9, 1914.

Application filed October 28, 1913. Serial No. 797,881.

To all whom it may concern:

Be it known that I, WILLIAM W. SHOE, citizen of the United States, residing at Philadelphia, Pennsylvania, have invented certain new and useful Improvements in Irons, of which the following is a specification.

My invention relates to an iron for domestic or laundry purposes, and it is designed to provide a simple and effective construction in which the maximum amount of heat may be delivered to the ironing surface and with the least amount of waste of the heat.

The invention consists in the features and combination and arrangement of parts hereinafter described and particularly pointed out in the claims.

In the accompanying drawings, Figure 1 is a side elevation of an iron embodying my invention. Fig. 2 is a vertical longitudinal section. Fig. 3 is a plan view of the lower or base member of the iron with the upper parts removed. Fig. 4 is a transverse sectional view taken vertically of Figs. 1 and 2 about centrally thereof and looking from the right. Fig. 5 is an end view of the right hand end of Fig. 1.

In these drawings, 1 is the base member carrying the ironing surface on its lower face, this member being of the general form of a tray and having upwardly projecting side edges 2; a rear wall 3 and a front wall 4. Within this tray is a combustion chamber made up of a shell 5, the walls of which are integrally formed with the base member so as to conduct the heat thereto from the burner tube 6, which extends lengthwise of the combustion chamber, about centrally thereof and about midway of its height. The combustion chamber or shell 5 is provided with an opening 7 in its top plate, extending from a point short of its rear end, through to the other end, as shown in Fig. 3. The shell forming the combustion chamber is open at its front end, as indicated at 8, in Fig. 2, and it is also open at its rear end because it terminates at the line 9, Figs. 2 and 3, leaving therefore a space between its rear end and the end wall 3. The shell forming the combustion chamber is, however, integrally connected with the rear wall 3 by a block or metal portion 10, which extends across the rear space and connects these parts. The combustion chamber, or rather the shell forming the com-

bustion chamber, terminates at the point 8, previously referred to, and is thus shorter than the base member 1, leaving a front space at 11 between the shell forming the combustion chamber and the front wall of the base. A post 12 rises in this space in line with the combustion chamber but separated slightly from the front end of the shell 5, this post being integrally formed with the base member as shown in Fig. 2. A top or cover member 13 is supported by studs integrally formed therewith, a pair 14 of these studs depending from the under side of the rear portion of the top plate or cover, and a second pair 15 depending from the cover or top plate at a point intermediate of its length. These studs rest upon a shield or diaphragm plate 16, which in turn rests upon the upper end of the post 12, and the upper surface of the reinforce or connecting piece 10. As shown in Fig. 2, the diaphragm or shield member is therefore supported at a point above the shell composing the combustion chamber, and it overlies the top opening of said combustion chamber and extends laterally to both sides of said opening, as shown in Fig. 4.

The top plate or cover has depending walls 17, which, as shown in Fig. 4, diverge from each other and conform substantially to the inclines of the side walls of the shell or combustion chamber 5, lying at a slight distance from the said shell as shown in Fig. 4. The lower edge of this depending skirt or wall of the top plate depends within and below the upper edge of the flange 2 of the base, being separated therefrom by a slight distance as indicated in Fig. 4, this depending edge being marked 17'. The skirt or depending wall of the top plate is also provided with a laterally extending flange 18, overlying and separated from the edge or flange 2 of the base. Openings 19 are provided in the side wall of the top or cover member, these openings being disposed in a row on each side of the cover member near the top thereof. The partition or diaphragm 16 lies in the plane of the centers of these openings and at a slight distance below the top plate or cover.

The handle 20 has a bail 21 resting on lugs 22 projecting up from the top or cover plate. Bolts 23 hold the handle in place. These bolts are screwed into the part 12 and the block 10 and they serve also to hold the top plate or cover in place as well as the shield

or partition 16, clamping all these parts together.

An opening 24 is formed in each side of the tray or base at the front part thereof, 5 said openings communicating with the interior space 11. Openings are also formed in the rear wall 3 at 25, communicating with the space at 9 and with the interior of the combustion chamber which is also open at its 10 rear end below the integral part 10. Besides the free space 26 left at the rear between the top plate and the upper edge of the rear wall 3 of the base, as shown in Fig. 5, there is a free space also present between the skirt 15 of the cover or top plate and the edge of the rear wall.

The gas supply pipe is supported in the rear wall 3 and front post 12, and it has slits on its under side so that the gas flame 20 will be thrown down and outwardly against the bottom and side walls of the combustion chamber. The walls of the combustion chamber have depending inner flanges 27 along the margin of the upper opening 7, 25 the purpose of which is to hold the heat and flame within the combustion chamber so that there will be a maximum conduction of heat through the walls of the combustion chamber to the base. The post 12 is in a position to 30 receive the heat and flame from the combustion chamber and this also acts to conduct heat to the base. The shield or diaphragm acts to retain the heat and flame in the combustion chamber, extending as it does over 35 to opening 7, and it serves also to prevent the excessive heating of the top or cover portion of the iron. It prevents the direct impingement of the flame or heat against the top plate and it provides for circulation of 40 air above the diaphragm and between it and the top plate of the cover. At the same time the heat may escape from below the diaphragm or partition out through the side 45 openings at the upper part of the side walls or skirt of the cover member.

The construction described provides for the proper circulation of the air and distribution of heat. Air enters the rear openings and the front openings to aid combustion 50, and air is drawn in between the flanges 2 and 17' aiding combustion and preventing excessive heating of the skirt of the cover or top part of the iron. Air is also free to enter at the back through the space at the top 55 and sides of the back wall.

I claim:—

1. In combination in a laundry iron, a base, an upper part, a shell between the upper part and base and integrally connected with the said base, said shell having sides and a top plate with an opening and forming a combustion chamber and a burner communicating with the combustion chamber within the shell.

2. In combination a base, an upper part, a

shell between the base and upper part and consisting of side walls extending up from the base and a top plate with an opening therein, said upper part having a skirt depending alongside the shell with an air space 70 between it and the shell and between it and the base, and a burner communicating with the interior of the shell, substantially as described.

3. In combination, a base, an upper part, a shell extending up from the base having an open top, with depending flanges along the margin of said open top, and a burner communicating with the interior of the shell, substantially as described. 75

4. In combination, a base, a shell connected to and extending up therefrom, and having an overhanging top with an opening therein, a cover portion having a skirt embracing the shell, a shield extending across 85 the top opening of the shell within the skirt and below, and spaced apart from, the cover portion, and a burner communicating with the interior of the shell, substantially as described. 80

5. In combination, a base, a shell connected with the base and forming a combustion chamber, and having a top opening, a cover portion having a depending skirt embracing said shell spaced apart therefrom and from 95 the base, a shield extending across the top opening of the shell and below, and spaced apart from, the cover, said depending skirt having openings in line with the space above the shield, substantially as described. 90

6. In combination, a base, a shell connected with the base and forming a combustion chamber, and having a top opening, a cover portion having a depending skirt embracing said shell spaced apart therefrom and from the base, a shield extending across the top opening of the shell and below, and spaced apart from, the cover, said depending skirt having openings in line with the space above and below the shield, substantially as 100 described. 105

7. In combination a base, a shell connected to the base, said shell being open at the top, and at front and rear, a cover portion spaced apart from the shell and base, and depending over the same; said base having a rear wall spaced apart from the rear of the shell and from the cover portion for the passage 115 of the air, the said base having openings at its front communicating with the interior space of the base and the open front end of the shell, substantially as described. 120

8. In combination a base, a shell connected thereto and extending up therefrom having an open front and rear end and an open top, said base having a rear wall and having also an opening communicating with the rear interior of the shell, said base having a front opening communicating with the interior of the base and shell, a cover por- 125 130

tion, and a burner communicating with the interior of the shell, substantially as described.

9. In combination, a base, a shell extending up therefrom, open at its top, front and rear, a cover portion, a rear wall spaced apart from the rear open end of the shell, a post extending up in front of and spaced apart from the front open end of the shell, and a shield plate between the top of the shell and the cover portion and spaced apart from each, and a burner communicating with the interior of the shell, said iron having air spaces at the rear, front and top of the shell, substantially as described.

10. In combination a base, a shell integral with and rising from said base having an opening in its top, front and rear, a post at the open front of the shell connected with the base and extending to a point higher than the shell, a rear wall with a space between it and the rear open end of the shell, an integral connection or block between the shell and the rear wall having its upper surface in the plane of the top of the post, a shield or diaphragm resting on the post and said block, a cover portion spaced apart from and above the shield, bolts for holding the cover portion, shield and base together, and a burner communicating with

the interior of the shell, substantially as described.

11. In combination a base, a shell rising from the base, a post at the front end of the shell and spaced apart from the front part 35 of the base, a cover portion inclosing the post and shell, a rear wall and a burner tube extending through the rear wall through the combustion chamber and supported at its end in the post, substantially 40 as described.

12. An iron comprising a base, a shell extending up therefrom having an overhanging top portion with an opening therein, a cover portion having a skirt depending 45 about the sides of the said shell, said cover portion with its depending skirt being spaced apart from the shell and base, a shield extending across the opening in the shell and spaced apart from said shell and 50 from the cover portion, the space above said shield and below the top of the cover portion communicating with the outside air, substantially as described.

In testimony whereof, I affix my signature 55 in presence of two witnesses.

WILLIAM W. SHOE.
